(57) **CLAIM**

The ornamental design for an automobile tire, as shown and described.

DESCRIPTION

FIG. 1 is a perspective view of front and left side of an automobile tire showing my new design;

FIG. 2 is a front view, a rear view being an identical image thereof;

FIG. 3 is a top plan view, a bottom view being an identical image thereof;

FIG. 4 is a left side view, a right side view being an identical image thereof;

FIG. 5 is a partially enlarged view of front part thereof; and, FIG. 6 is an enlarged end view at A—A shown in partially enlarged view of front part thereof.

The portions of the article in broken lines are shown for illustrative purposes only and form no part of the claimed design.
